UNITED STATES PATENT OFFICE

HENRY W. ROOS, OF CINCINNATI, OHIO

ADJUSTABLE SHORE

Application filed March 13, 1930. Serial No. 435,450.

This invention relates to apparatus for forming concrete floor molds, and particularly to temporary supports or shores on which the molds are supported.

It is frequently desirable to construct one portion of a floor of a thicker slab of concrete than another portion where the thick portion is required to carry a heavier load than the other part. The forms for the mold for the thick slab are assembled in a lower plane than those for the thin slab, with a substantially vertical wall between them, the difference in thickness between the two slabs being varied according to the difference in the loads to be carried thereon.

The principal object of this invention is the provision of a shore which is simple in construction, efficient in use, and adapted to support the floor forms on one side at a higher level than those on the other side.

Another object of the invention is the provision of a shore of this kind adapted to support the floor forms on one side in a higher plane than those on the other side, said shore being adjustable to vary the vertical distance between said planes.

Still another object of the invention is the provision of a shore adapted to support a plurality of floor forms at their corners, said shore being adjustable to support one of said forms in a different horizontal plane than the others.

To these and other ends, the invention consists in the construction and arrangement of parts that will appear from the following description when read in conjunction with the accompanying drawings, the novel features being pointed out in the claims following the specification.

In the drawings:

Fig. 1 is a fragmentary plan view of a floor mold illustrating one embodiment of the invention;

Fig. 2 is a fragmentary vertical section of the same, taken substantially on line 2-2 of

Fig. 1, and looking in the direction of the arrows at said line;

Fig. 3 is a section on line 3-3 of Fig. 4, looking in the direction of the arrow at said line and showing one of the floor forms detached;

Fig. 4 is a side elevation of the parts shown in Fig. 2;

Fig. 5 is an elevation of the other side of the shore shown in Fig. 4;

Fig. 6 is a perspective view of an adjustable carrier shown in Fig. 4;

Fig. 7 is a perspective view of another shore shown in Fig. 1;

Fig. 8 is a plan view of the same;

Fig. 9 is a perspective view of a carrier shown in Fig. 8;

Fig. 10 is a front elevation of a slightly modified form of the shore shown in Fig. 4;

Fig. 11 is a side elevation of the same;

Fig. 12 is a plan view of the same showing a fragment of a floor form supported thereon and another detached therefrom, and

Fig. 13 is a section taken on line 12-12 of Fig. 11 and looking in the direction of the arrows at said line.

Referring specifically to the drawings, in which like reference numerals refer to the same parts in the several views, 1 represents a floor form of well known type. The forms 1 are substantially rectangular or square in form, and are cut away at their corners to fit around the tops of shores 2, 3 and 4 on which they are supported to form a floor mold.

In the embodiment illustrated, the forms 1' are assembled in a lower plane than the forms 1'' for the purpose of forming a thicker slab thereon. Four of the forms 1 are shown supported on each of the shores 2, 3 and 4, those supported on the shores 2 all being in the same plane, while two of those supported on the shore 3 are supported at a lower plane than the other two, and one of those supported on the shore 4 is supported at a lower plane than the other three. The

shores 2 are of usual construction, each having four arms, each of which is adapted to engage two of the adjacent floor forms. By reference to Fig. 2, in which one of the shores 3 is shown in elevation, it will be noted that this shore has two arms 5 and 6 of usual construction. The arm 5 is mounted on a bracket 7 supported in a lower plane than the bracket 8 on which the arm 6 is mounted. The arm 5 engages and supports two of the floor forms 1', and the arm 6 two of the forms 1''. The bracket 8 is secured to or formed integral with an upright supporting member 9 and flush with its upper end. A top 10 of a size and shape to cooperate with the corners of two adjacent forms 1'' is secured to the top of the support 9 and flush with one side thereof, as shown in the drawings. The support 9 is secured at its lower end to an inverted U-shaped bracket 11 adapted to be mounted on a post or other suitable support.

The arm 6 is pivotally mounted on the bracket 8 and retained in the operative position shown in Fig. 2 by a wedge 12 or other suitable means arranged in an opening in the bracket 8. By removing the wedge, the arm is free to fall to an inoperative position, to release the forms, leaving the slab of new concrete supported on the top 10.

The arm 5 is pivoted on the bracket 7 and engages and supports two of the forms 1' at their corners. The bracket 7, see Fig. 6, is mounted on a carrier member 15 adapted to be adjustably secured to the support 9. The member 15 is substantially rectangular in form, and the bracket 7 is arranged at substantially right angles thereto at a point intermediate its side edges and substantially flush with its top and bottom edges. At the upper edges of the carrier member 15 and the bracket 7 is a top 16, and flush with the inner side opposite the bracket 7 of the carrier. The top 16 is in all respects like the top 10, and is adapted to cooperate with two of the adjacent forms 1', which are supported on the arm 5 pivoted on the bracket 7.

The upright support 9 is provided with a plurality of vertically aligned openings or slots 17 on each side of the bracket 8 or between said bracket and each of its vertical side edges. The carrier 15 is also provided with vertically aligned openings or slots 18 on each side of its bracket 7 adapted to register with the slots 17 for the reception of bolts 20 or other suitable means for securing the carrier to the support 9. By removing the bolts 20, the carrier with its bracket 7 may be removed from the support and secured thereto in another position, with its top 16 arranged in another horizontal plane nearer to or farther from the plane of the top 10. It will be noted that by this arrangement, the top 16 and bracket 7 may be secured to the support in a plurality of horizontal planes at different distances below the top 10 and

bracket 8. If desired, the sides of the carrier 15 may be reinforced by means of plates welded thereto, as shown.

The shore 4 is shown in detail in Figs. 7, 8 and 9, and will now be described. It comprises an upright support 25 having two walls 26 and 27 arranged substantially at right angles to each other. On each of the outer faces of the walls 26 and 27 is a bracket 8' in all respects like the bracket 8 and on which form supporting arms 6' are adapted to be pivotally mounted. The brackets 8' project outwardly from their respective walls, and are arranged substantially flush with the upper edges thereof. Mounted on the upper edges of the brackets 8' and the walls 26 and 27, and substantially flush with the inner surfaces of said walls is a top 28. The top 28 is like the top on the shore 2 but being cut away along the inner surfaces of the walls 26 and 27 it is only of three-fourths the area and is adapted to cooperate with the corners of only three of the forms 1'' which are mounted on the arms 6'. An angle iron or bracket 31 is secured to the outer surface of the wall 26 preferably by welding, and which serves to reinforce the wall, and at its outer edge has a flange 32 arranged at substantially right angles thereto. A similar angle iron 33 is secured to the outer surface of the wall 27 having the flange 34 similarly arranged at substantially right angles thereto.

Arranged between the inner sides of the walls 26 and 27 is a carrier member 35. The member 35 comprises two walls 36 and 37 arranged at substantially right angles to each other to correspond to the arrangement of the walls 26 and 27. Secured to one of the walls, the wall 37 in the embodiment illustrated, and flush with its upper end, is a bracket 7' in all respects like the bracket 7, which is arranged in a vertical plane substantially intermediate the vertical side edges of the wall 37. A top 38 is secured to the upper edges of the walls 36 and 37, and the bracket 7' with its inner edges flush with the inner sides of the walls 36 and 37.

The wall 26 is provided with a plurality of vertically aligned openings or slots 39 which extend through the bracket 31, and the wall 27 is provided with correspondingly arranged slots or openings 40 and in the same horizontal planes as the openings 39. The walls 36 and 37 of the carrier 35 are each provided with vertically aligned openings 41 and 42 adapted to register with one or another of the openings 39 or 40 in the walls 26 and 27 when the carrier is placed in the angle between them, for the reception of bolts 44 whereby the carrier is secured to the support. By removing the bolts, the carrier is freed from the support and may be moved vertically thereon, when the bolts may be reinserted in newly aligned openings for securing

the carrier to the support in a new position with its top nearer to or farther from the top 28 on the support. The shore 4 is especially adapted to be used at a point where a corner of a thick floor slab is joined with the thin slab, the corner of the form 1 being supported on and cooperating with the top of the carrier 35 in a plane arranged at the desired distance below the top 28 of the support which cooperates with three forms 1" supported on the brackets 8' in the higher plane.

A vertical opening is formed between the edges of the thick slab mold and the thin slab mold, which is usually filled by means of a wall of sheet material secured to the marginal flanges of the forms 1' and 1" and arranged vertically in the opening. This construction sometimes interferes with the removal of the floor forms since the forms are connected to each other. In the present embodiment, these vertical walls can be mounted directly on the shores, and to this end, the flanges 32 and 34 are provided with openings for the reception of bolts, whereby the vertical walls 45 may be secured thereto. The shores 3 are provided with similar flanges 46 to which the walls 45 may also be secured.

The flanges 32, 34 and 46 are cut away at their upper ends to provide a clearance for the downwardly projecting marginal flanges on the floor forms, and the walls 45 overlap said flanges at the top and have outwardly projecting flanges at their ends adapted to abut the flanges 32, 34 and 46.

Referring to Figs. 10 to 13 inclusive, a slightly modified form of the shore shown in Figs. 4 and 5 is illustrated. In constructing floor molds in which a beam or girder is to be formed, shores are employed on which the floor forms are supported on one side and the other side lies in the plane of the side of the beam mold, and the sides of the beam forms are secured directly on flanges on the shores. In Figs. 10 to 13 above referred to, a shore is illustrated which is convertible so that it may be used for supporting floor and beam forms or interchanged with the shores 3 described above for supporting floor forms at the points where a thick slab joins a thinner one. The interchangeable shore comprises an upright support 50, mounted on a bracket 51, and having a bracket 52 secured thereto intermediate its lateral edges and flush with its upper end. A form supporting arm 53 is pivoted to the bracket, and a top 54 is mounted on the upper ends of the support and bracket and flush with the inner face of the support 50. The support 50 is provided with a plurality of slots or openings 55 arranged in two vertical lines extending throughout the length of the support on opposite sides of the bracket 52. A carrier 56 in all respects like the carrier 15 is provided with openings 18 adapted to register with the openings 55 for the reception of

bolts, whereby the carrier may be adjustably secured to the inner face opposite the bracket 52 of the support.

Angular brackets 57 are secured to the outer face of the support 50 flush with its vertical side edges and provide the outwardly extending flanges 58, each of which is provided with vertically alined slots 59. When the carrier 56 is detached from the support, the shore may be arranged in the plane of the side of the beam opening, and the beam forms having outwardly projecting flanges at their ends may be secured to the flanges 58 by means of bolts in the usual manner.

Although the invention has been described with reference to certain details of construction, it will be understood that this application is intended to cover such changes or modifications as come within the spirit of the invention or scope of the following claims.

I claim:

1. A shore for supporting floor molds in different horizontal planes, comprising a support, a form supporting bracket fixed to one side of said support, and a form supporting bracket adjustably mounted on the other side of said support.

2. A shore for supporting floor molds in different horizontal planes, comprising a support, a form supporting bracket fixed to one side of said support, a carrier adjustably mounted on the other side of said support, and a form supporting arm pivoted on said carrier.

3. A shore for supporting floor molds in different horizontal planes, comprising a support, a form supporting bracket fixed to one side of said support, a top on said support flush with one side thereof, a carrier adjustably mounted on the other side of said support, a top on said carrier flush with said other side of said support, and a form supporting bracket on said carrier.

4. A shore for supporting floor molds in different horizontal planes comprising a support having two vertical walls arranged at substantially right angles to each other, a form supporting bracket on the outer surface of each of said walls, and a form supporting bracket adjustably mounted in the angle between said walls.

5. A shore for supporting floor molds in different horizontal planes comprising a support having two vertical walls arranged at substantially right angles to each other, a form supporting bracket on the outer surface of each of said walls, a carrier adjustably mounted in the angle between said walls, and a form supporting arm pivoted on said carrier.

6. A shore for supporting floor molds in different horizontal planes comprising a support having two vertical walls arranged at substantially right angles to each other, a form supporting bracket on the outer surface

of each of said walls and flush with the upper edges thereof, a top mounted on the upper edges of said brackets and support and flush with the inner surfaces of said walls, and a form supporting bracket adjustably mounted between said walls.

7. A shore for supporting floor molds in different horizontal planes comprising a support having two vertical walls arranged at substantially right angles to each other, a form supporting bracket on the outer surface of each of said walls, a carrier adjustably mounted in the angle between said walls, said carrier comprising two walls arranged at substantially right angles to each other, a form supporting bracket secured to one of said walls and arranged between them, and a top mounted on said walls and the upper end of said bracket.

8. A shore for supporting floor forms in different horizontal planes for molding a floor of thick and thin slabs, said shore comprising an upright support, a form supporting bracket secured to one side of said support, a form supporting bracket mounted on the other side of said support, and flanges arranged in the plane of the side of the thick slab and arranged on said support for supporting a form for molding a vertical side wall on the thick slab.

9. A shore for supporting floor molds in different horizontal planes, comprising a support, a top on said support arranged in a horizontal plane and adapted to directly engage a slab to be formed in the higher plane, a bracket on said support for supporting a form for the mold in the plane of said top, a second bracket mounted on said support, a top on said second bracket arranged in a different horizontal plane from the top on the support and adapted to directly engage a slab to be formed in the lower plane, and means on said second bracket for supporting a form for the mold in the lower plane.

10. A shore for supporting floor molds in different horizontal planes, comprising a support, a top projecting from one side of said support and adapted to directly engage a slab to be formed in the higher plane, a bracket on the same side of said support for supporting a form for the mold in the plane of said top, a second bracket on the other side of said support, a top on said second bracket arranged in a different horizontal plane from the top on the support and adapted to directly engage a slab to be formed in the lower plane, and means on said second bracket for supporting a form for the mold in the lower plane.

11. A shore for supporting molds in different horizontal planes, comprising a support, a top on said support adapted to directly engage a slab to be formed in the higher plane, means movable on said support for detachably supporting a form in the

plane of said top, a bracket on said support, a top on said bracket arranged in a different horizontal plane from the top on the support and adapted to directly engage a slab to be formed in the lower plane, and means movable on said bracket for detachably supporting a form for the mold in the lower plane.

In witness whereof, I have hereunto signed my name.

HENRY W. ROOS.
